UNITED STATES PATENT OFFICE.

JAMES M. WALSH, OF MILWAUKEE, WISCONSIN, ASSIGNOR TO JAMES M. WALSH CO., OF MILWAUKEE, WISCONSIN, A CORPORATION OF DELAWARE.

MARTINGALE STRAP AND CONNECTER.

Application filed February 20, 1925, Serial No. 10,569. Renewed November 25, 1925.

This invention relates to improvements in martingale strap and connecters.

In the ordinary harness construction, the martingale strap is formed with a loop provided with a ring to which the side straps of the harness are connected. A belly-band strap extends loosely through the loop and in use, the ring drops downwardly and exposes the inner end portion of the loop to the wear of the belly-band strap which works back and forth therein. Furthermore, in the ordinary construction the dropping downwardly of the martingale ring permits the hook members, which connect the side straps to the ring, to become accidentally disengaged therefrom.

It is one of the objects of the present invention to overcome the above mentioned objectionable features and provide a martingale strap and connecter in which the martingale ring will be retained in its adjusted position, and is so shaped and positioned as to eliminate wear from the belly-band strap.

A further object of the invention is to provide a martingale strap and connecter in which the ring member will be retained in its adjusted position and the hook members connected thereto will also be pivotally retained in aligned position therewith.

A further object of the invention is to provide a martingale strap and connecter having a novel means for locking the hook members to the martingale ring, and which means will prevent the accidental disengagement of the hook members from the martingale ring.

A further object of the invention is to provide a martingale strap and connecter in which the hook members are formed with sewing slots for connecting side straps to the hook members.

A further object of the invention is to provide a martingale strap and connecter which is of simple construction, is strong and durable, and is well adapted for the purpose described.

With the above and other objects in view, the invention consists of the improved martingale strap and its parts and combinations as set forth in the claims, and all equivalents thereof.

In the accompanying drawing in which the same reference characters indicate the same parts in all of the views:

Fig. 1 is a lower side view of one end portion of a martingale strap provided with the improved connecter and hook members, and a portion of the belly-band or strap;

Fig. 2 is a vertical sectional view taken on line 2—2 of Fig. 1; and

Fig. 3 is a sectional detail view of one of the hook members and a portion of the martingale ring showing the manner of disengaging the hook member from the ring.

Referring to the drawing, the numeral 5 indicates the looped end of a martingale strap which is provided with a guard flap 6 on its inner or upper side. The looped portion extends through an elongated curved slot 7 formed in the martingale ring 8. Said curvature extends away from the end of the strap loop so that in inserting the looped portion 5 therethrough, the said portion will be bent outwardly in a curve 75 at right angles to the curve of the strap loop, as clearly shown in Figs. 1 and 2, to conform to the shape of the slot.

As thus connected, the ring will be firmly held in its adjusted position with relation to the strap, and eliminate wear on the strap. Said ring is also formed with two eyes 9 extending at diverging angles from the elongated slotted portion of the ring. The openings forming the eyes 9 are elongated or of egg-like formation, with the portions of the larger diameter at the outer ends to pivotally receive the hook portions 10 of side strap hook members 11. The entrance throats or openings 12 of the hook members 11 are of less width than the thickness of the metal of the eyed portions 9 of greater diameter, so that in ordinary use the hook members can not accidentally disengage the eyes. The inner adjacent side portions 13 of the eyes 9 are of less thickness than the other portions of the eyes to permit each hook member to be engaged or disengaged therefrom when said hook member is swung upwardly a quarter turn, with reference to Fig. 1, and then turned to register its throat 12 with the side portion 13 of the eye 9. When in this position the hook member can then be turned outwardly to disengage the eye in the manner shown in Fig. 3. As it is impossible for the hook members to swing to the positions just described while in use, the said parts can not accidentally disengage each other. The hook members 11 are provided with eyes 14 to

105
110

receive side straps (not shown) and are also provided with sewing slots 15 for sewing the side straps to the hook members.

The martingale ring portion 8' which 5 extends through the loop 5 of the martingale strap is of sufficient width to prevent the edge of the belly-band strap 16 from rubbing against the end portion of the loop 5 and thus eliminates wear thereon.

10 The guard flap 6 is positioned to be interposed between the martingale ring and hook members and the animal to prevent the metal parts from rubbing against the animal.

15 From the foregoing description, it will be seen that the construction provides a very simple means for connecting the parts together or separating said parts, and when connected, the parts will be maintained in 20 proper position with the minimum amount of wear on the straps.

What I claim as my invention is:

1. A martingale strap and connector, comprising a martingale strap having a loop, a 25 ring member having an elongated slot through which the loop extends and also having an eyed portion provided with an entrance part of less thickness than other portions, and a hook member having an entrance 30 throat of less size than the thickness of the major portion of the eyed part of the ring member, but of greater size than the entrance part thereof to permit connection together of the parts.

35 2. A martingale strap and connector, comprising a martingale strap having a loop, a ring member having a curved elongated slot through which a portion of the strap loop 40 extends and is bent to conform thereto, said ring member also having eyed portions provided with entrance parts of less thickness than other portions, and hook members having 45 entrance throats of less size than the thickness of the major portions of the eyed parts but of greater size than the entrance part thereof to permit connection together of the parts.

50 3. A martingale strap and connector, comprising a martingale strap having a loop, a ring member having an elongated slot the 55 opposite walls of which are curved at right angles to the curvature of the loop and through which the looped portion of the strap extends and is bent to conform thereto, said ring member also having eyed portions,

and hook members engaging said eyed portions.

4. A martingale strap and connector, comprising a martingale strap having a loop, a ring member having an elongated slot 60 through which the loop extends and also having eyed portions provided with entrance parts of less thickness than other portions, and hook members having entrance throats of less size than the thickness of the major 65 portions of the eyed parts but of greater size than the entrance parts thereof to permit connecting the parts together.

5. A martingale strap and connector, comprising a martingale strap having a 70 loop, a ring member having an elongated slot curved in a direction at right angles to the curvature of the loop and through which slot a portion of the loop extends and is bent to conform thereto, said ring member 75 also having eyed portions of elongated form which extend divergently from the slotted portion, the inner adjacent edges of the eyed portions being of less thickness than other portions to form entrances to the 80 eyed portions, and hook members having side entrance throats of less size than the thickness of the major parts of the eyed portions but of greater size than the entrance parts thereof to permit connecting the parts 85 removably together.

6. A martingale strap and connector, comprising a martingale strap having a loop, a ring member having an elongated slot 90 curved in a direction at right angles to the curvature of the loop and through which slot a portion of the loop extends and is bent to conform thereto, said ring member also having eyed portions of elongated form which extend divergently from the slotted 95 portion, the inner adjacent edges of the eyed portions being of less thickness than other portions to form entrances to the eyed portions, hook members having side entrance throats of less size than the thickness of the major parts of the eyed portions but of greater size than the entrance 100 parts thereof to permit connecting the parts removably together, and a guard member connected to the strap loop and extending on one side of the martingale ring and portions of the hook members.

In testimony whereof, I affix my signature.

JAMES M. WALSH.
